US00D669100S

(12) **United States Design Patent**
Ringer et al.

(10) **Patent No.:** **US D669,100 S**
(45) **Date of Patent:** **** Oct. 16, 2012**

- (54) **RINSE TANK FOR AN AGRICULTURAL MACHINE**
- (75) Inventors: **Chad Ringer**, Trafalgar, IN (US); **Justin Honegger**, Plainfield, IN (US)
- (73) Assignee: **ET Works, LLC**, Mooresville, IN (US)
- (**) Term: **14 Years**
- (21) Appl. No.: **29/397,315**
- (22) Filed: **Jul. 14, 2011**
- (51) **LOC (9) Cl.** **15-03**
- (52) **U.S. Cl.** **D15/28**
- (58) **Field of Classification Search** **D15/10, D15/13-17, 28, 21, 27; D12/218; D23/200, D23/202, 213; 239/683, 687, 72, 289, 722; 414/725, 912; 37/442, 403; 111/118; 137/544; 220/587, 565, 567.1; 210/532.2; 123/563; 222/185.1, 608**

CLAIM

The ornamental design for a rinse tank for an agricultural machine, as shown and described.

DESCRIPTION

FIG. 1 is a perspective view of a rinse tank for an agricultural machine showing our new design;

FIG. 2 is a rear elevational view thereof;

FIG. 3 is a front elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing of portions of the rinse tank is included for illustrative purposes only and forms no part of the claimed design.
